Claims priority, application Germany Dec. 10, 1960

7 Claims. (Cl. 163—37)

The present invention relates to pumps.

More particularly, the present invention relates to injection pumps adapted to be used with internal combustion engines for supplying fuel to the cylinders thereof.

Although injection pumps are at the present time highly developed, nevertheless it is still necessary to provide two basic types of injection pumps. One type is designed for operation at relatively low speeds and the other type is designed for operation at relatively high speeds. Injection pumps are required to operate at very high pressures in order to be able to transmit the fuel to the cylinders of the engine. Because of these high pressures there is always the problem of preventing fuel from leaking back to the inlet of the pump during the pressure strokes thereof. In pumps which are designed for slow speed operation, this problem is taken care of by providing in the pump a valve means which will reliably prevent fuel from flowing back to the inlet of the pump during the pressure strokes thereof, but such pumps cannot be used for high speed operation because the inertia of the valve means prevents the valve means from maintaining the inlet of the pump closed off from its pumping chamber during the entire part of each pressure stroke. It is therefore necessary at the present time to provide for high speed operation a pump which does not have such a valve means and which is capable during high speed operation of preventing flow of fuel back to the inlet of the pump. However, these pumps which are designed for high speed operation cannot prevent flow of fuel back to the inlet of the pump if these pumps operate at a relatively low speed. The only way to prevent fuel from flowing back to the inlet of the pump with a pump which does not include a valve means and which is designed for high speed operation is to provide the pump with cylinders and pistons of extremely large diameters to greatly increase the length of the path along which the fuel would have to flow back to the inlet of the pump, and since it is essential that modern injection pumps be quite small and compact, it is not feasible to provide pumps of relatively large diameters at their cylinders and pistons.

It is, therefore, a primary object of the present invention to provide an injection pump which is capable of operating both at low and at high speeds without any danger of leakage of fuel back to the inlet of the pump during the pressure strokes thereof while at the same time maintaining the dimensions of the pump relatively small and compact so that the pump of the invention while having a perfectly satisfactory size enabling it to be used without difficulty with modern engines at the same time can be used either for operations at relatively low speeds or for operations at relatively high speeds so that it becomes unnecessary to provide two basically different pump designs depending upon whether the pump is to operate at low speeds or high speeds.

Another object of the present invention is to provide an injection pump which includes all of the best features of both the slow speed and the high speed designs while at the same time eliminating all of the disadvantages thereof.

Still another object of the present invention is to provide an injection pump which is of an extremely simple design and which includes no more parts than conventional pumps while at the same time being capable of operation

2

at both low and high speeds without any danger of leakage of fuel back to the inlet of the pump.

It is furthermore an object of the present invention to provide an injection pump which is rugged and reliable in operation and which will be capable of operating perfectly not only at relatively low and high speeds but also with all types of fuels and under all operating conditions.

With these objects in view, the invention includes, in an injection pump which is adapted to operate at relatively low and at relatively high speeds, a cylinder having in its interior a pumping chamber; an inlet passage means provides for flow of fuel into the pumping chamber and a discharge passage means provides for flow of fuel out of the pumping chamber, and a piston means is located in the cylinder for reciprocation therein along pressure and suction strokes. A control means cooperates with the cylinder for opening the inlet passage means during each suction stroke of the piston means and for closing the inlet passage means during each pressure stroke of the piston means, and this control means opens the discharge passage means during each pressure stroke of the piston means and closes the discharge passage means during each suction stroke of the piston means. Under certain operating conditions, as when the pump operates with a relatively light fuel or as when the parts become relatively worn, this control means is incapable of preventing leakage of fuel back to the inlet passage means when the pump operates at relatively low speeds. A valve means is located in the path of fuel flow through the inlet passage means to the pumping chamber for closing off the pumping chamber from the inlet passage means during the pressure strokes of the piston means when the pump operates at relatively low speeds, and thus, in accordance with the present invention, the control means and the valve means cooperate to prevent leakage of fuel back to the inlet passage means during the pressure strokes of the piston means when the pump operates at relatively low speeds and when the pump operates at relatively high speeds.

The novel features which are considered as characteristic for the invention are set forth in particular in the appended claims. The invention itself, however, both as to its construction and its method of operation, together with additional objects and advantages thereof, will be best understood from the following description of a specific embodiment when read in connection with the accompanying drawing, in which one possible injection pump according to the present invention is illustrated in an axial sectional elevation with the discharge passages of the pump shown in an axial sectional plane which is angularly displaced from the axial sectional plane in which the remainder of the structure of the drawing is illustrated.

In the particular example which is illustrated in the drawing, the pump of the invention has one cylinder and piston and it is designed to supply fuel to an engine of four cylinders, but it is to be understood that the invention is applicable to pumps of any desired number of cylinders and can supply fuel to engines having any desired number of cylinders.

The pump illustrated in the drawing includes a housing having a lower part 1 and an upper part 2 fixed to the lower part 1. This lower housing part 1 rotatably supports the drive shaft 3 of the pump, this drive shaft 3 being connected in a known way to the crankshaft of the engine so as to operate the pump in proper synchronization with the engine. The drive shaft 3 fixedly carries at its upper end, as viewed in the drawing, a cam 4 having at its outer periphery four downwardly directed camming portions 5 which are uniformly distributed about the axis of the coaxial elements 3 and 4. A spring 6, in a manner described below, urges the camming portions 5 against rollers 7 which are supported for free rotation respectively about axes which are perpendicular to and

located in a plane normal to the axis of the shaft 3, these rollers 7 being located at equal radial distances from the axis of the shaft 3 and being displaced with respect to each other by 90° about the axis of the shaft 3. Thus, during each revolution of the shaft 3 this shaft together with the cam 4 will be reciprocated back and forth along the axis of the shaft 3 four times. The rollers 7 are supported for rotation by the shafts which are in turn carried by the lower housing part 1 in the manner shown in the drawing.

Within the upper housing part 2 is fixedly located a cylinder 8 which forms the cylinder of the pump, and the spring 6 bears at its upper end, as viewed in the drawing, against a downwardly directed shoulder adjacent the lower end of the cylinder 8, as viewed in the drawing. The other end of the spring 6 bears against a washer 9 which is carried by an upwardly directed shoulder of an elongated member 10 so that this member 10 is pressed by the spring 6 against the cam 4 and through the member 10 the spring 6 maintains the cam 4 against the rollers 7. The cam 4 fixedly carries an axially extending pin 11 which extends into a radial notch formed in the lower end of the member 10, as viewed in the drawing, this radial notch having a width corresponding to the diameter of the pin 11, so that as a result with this construction the member 10 is constrained to rotate and reciprocate with the cam 4. It will be noted that the member 10 has at its lower end, as viewed in the drawing, a convex end face extending into a recess formed in the upper face of the member 4 and engaging this member 4 in its recess. As will be apparent from the description below, the lower solid portion of the member 10 shown in the drawing forms a piston means while the upper tubular portion of the member 10 forms a control means, and of course the control means and the piston means formed by the tubular and solid portions of the member 10 both reciprocate and rotate as a unit in response to the action of the drive means formed by the parts 3-7.

The part of the cylinder 8 in which the tubular portions or control means of the member 10 is located forms the pumping chamber of the cylinder 8, and during reciprocation of the member 10 the piston means formed by the solid portion thereof will reciprocate along pressure and suction strokes, as will be apparent from the description which follows. A valve means 12 is located within the tubular portion of the member 10. This tubular portion has a stepped bore. These stepped portions 13, 14, 15 of the tubular part of member 10 have progressively increasing diameters, as shown in the drawing, and the shoulder formed between the portions 14 and 15 of the bore of the tubular portion of member 10 forms a valve seat for the valve means. The valve member is provided beneath the portion thereof which engages the valve seat with elongated guide fins slidably engaging the inner surface of the tubular portion of member 10 in the bore portions 13 and 14 thereof, as shown in the drawing.

A spring 16 forms part of the valve means and operates with the valve 12 to urge it toward its closed position. The upper end portion of the spring 16, as viewed in the drawing, engages a transverse wall 17 of an elongated sleeve member axially slidable within the upper bore portion 15 of the member 10, and the sleeve which has the wall 17 has a very close sliding fit in the bore portion 15 so as to be fluid-tight at its slidable engagement with the member 10. The sleeve has at its upper end, as viewed in the drawing, an outwardly directed annular flange 18 which, in the illustrated position of the parts shown in the drawing, engages an inwardly directed annular flange 19 of a sleeve 20 which is axially slidable within the upper housing part 2. A spring 22 which bears at one end against a cover member 23 which closes the upper housing part 2 bears at its opposite end against the upper end of a cylindrical cap member 24 having a lower end face, as viewed in the drawing,

which is convex and which is urged by the spring 22 against the transverse wall portion 17, so that the spring 22 maintains the cap 24 in the position shown where this cap acts on the wall 17 to maintain the flange 18 in engagement with the flange 19. Of course, the spring 22 is stronger than the spring 16.

The sleeve 20 is formed with a cutout which receives a pin 27 which is eccentrically fixed to an adjusting member 28. The turnable adjusting member 28 is supported for turning movement in a sleeve 29 which is threaded into a suitable bore of the upper housing part 2, and this member 28 has an outwardly directed flange engaging a shoulder in the interior of the member 29, as shown in the drawing. To the left of this flange the member 28 has an elongated shaft portion adapted to be turned in any suitable way by the operator, and the sleeve 30 is threaded into the member 29 and engages the member 28 so as to restrain the member 28 against axial movement while permitting angular movement thereof. Thus, the operator by adjusting the angular position of the member 28 will adjust the elevation of the sleeve 29 in the housing 2.

The housing 2 is formed intermediate its ends with an opening 32 through which fuel reaches the pump. This opening 32 may be suitably threaded so as to be connected to a suitable conduit leading from any gear pump or the like which pumps fuel from the tank to the opening 32 so that in this way the fuel is delivered to the pump. The cylinder 8 is formed with an inlet passage means through which fuel flows to the pumping chamber 30 in the interior of the cylinder 8, and this inlet passage means includes the annular groove 33 formed in the exterior of the cylinder 8 and the series of openings 34 providing communication between the annular groove 33 and the interior of the cylinder 8. In the illustrated example there are four sets of openings 34 displaced by 90° with respect to each other about the axis of the cylinder 8, and in each set of openings 34 there are three openings located one above the other as illustrated. The control means which is formed by the tubular portion of the member 10 is formed with one set of three openings 35 located one above the other, and during reciprocation and rotation of the member 10 the openings 35 will successively come into communication with the successive sets of openings 34 which are distributed about the axis of the cylinder 8. The angular position of the set of openings 35 of the control means formed by the tubular portion of the member 10 with respect to the four sets of openings 34 which form the inlet passage means is such that during each suction stroke of the piston means formed by the lower part of the member 10, when this member 10 moves downwardly, as viewed in the drawing, the set of openings 35 communicates with one of the sets of openings 34 while during each pressure stroke, when the member 10 moves upwardly, as viewed in the drawing, the set of openings 35 is situated between a pair of sets of openings 34 out of communication therewith so that in this way the control means opens the inlet passage means during each suction stroke and closes the inlet passage means during each pressure stroke of the piston means.

The upper housing part 2 is formed with four openings 38 which are internally threaded so as to be connected with conduits leading to the several cylinders of the internal combustion engine, and the cylinder 8 is formed with a discharge passage means in the form of four openings 37 which respectively communicate with the openings 38 and which are respectively coaxial therewith, as indicated in the drawing. The four openings 37 are also displaced by 90° with respect to each other about the axis of the cylinder 8, but these openings 37 are respectively displaced about the axis of the cylinder 8 by an angle of 45° with respect to the four sets of openings 34, so that for this reason the section showing the openings 37 and 38 is different from that in which the openings 34 are located. The control means formed

by the tubular portion of the member 10 is additionally formed with an opening 36 which during reciprocation and rotation of the member 10 successively comes into and out of communication with the several discharge passages 37. The angular position of the opening 36 with respect to the openings 37 is such that during each pressure stroke of the piston means formed by the lower part of the member 10 the opening 36 will communicate with one of the openings 37 while during each suction stroke the opening 36 will be situated between and spaced from a pair of the openings 37 so that in this way the control means provides communication between the pumping chamber of the cylinder 8 and the discharge passage means 37 during each pressure stroke and cuts off communication between the pumping chamber of the cylinder 8 and the discharge passage means 37 during each suction stroke of the piston means formed by the lower, solid part of the piston 10.

The parts are shown in the drawing in the position they take at the end of one of the suction strokes at the point when a succeeding pressure stroke is about to begin. Thus, at this time the valve means 12 is closed. During the continued turning of the shaft 3 the member 10 will of course move upwardly so that the piston means formed by the lower portion of the member 10 will move along a pressure stroke. As a result the valve 12 remains closed and the fuel in the space between the valve 12 and the wall 17 is compressed. The pressure required to force fuel through the injection nozzle of a cylinder of the internal combustion engine is greater than that required to compress the spring 22 so that during the initial part of the pressure stroke the wall 17 together with a cap 24 move upwardly along the axis of the cylinder 8. The cap 24 is guided for movement by the pin 25 which is carried by the cover 23 and which extends through the spring 22, and the cap 24 is capable of easily sliding axially along the pin 25. Thus, during the initial part of the pressure stroke the spring 22 will be compressed, the cap 24 and the wall 17 will move upwardly, and the volume of the space between the wall 17 and the valve 12 will remain unchanged so that no fuel will be displaced at this time through the discharge passage means. However, before the end of the pressure stroke the cap 24 will engage the bottom end of the pin 25, as viewed in the drawing, so that continued axial displacement of elements 17 and 24 will be prevented, and thus at this time during the continued movement of the piston means along its pressure stroke the valve 12 will approach the wall 17, compressing the spring 16 and forcing fuel out through the discharge passage means.

During the next following suction stroke the opening 36 of the control means does not communicate with any of the openings 37 which form the discharge passage means, but at this time the set of openings 35 of the control means communicate with one of the sets of openings 34 so that fuel flows into the pumping chamber of the cylinder 8 through the openings 35 and of course at this time, the valve 12 automatically opens so that the fuel flows into the space between the valve 12 and the wall 17. It will be noted that because the flange 18 engages the flange 19 the wall 17 cannot follow the member 10 during the entire suction stroke of the piston means formed by the lower portion of the member 10, so that as a result a suction is created between the wall 17 and the valve 12 automatically opening the valve 12 to admit fuel into the space between the wall 17 and the valve 12. At the beginning of the next following pressure stroke the valve 12 closes automatically, as indicated in the drawing.

It is possible to regulate the amount of fuel displaced from the cylinder 8 during each pressure stroke by adjusting the angular position of the adjusting member 28. The maximum amount of fuel will be delivered by the pump of the invention when the member 28 is turned to raise the sleeve 20 in opposition to the spring 22 so as

to locate the lower end portion of the cap 24 permanently in engagement with the bottom end of the pin 25. As a result during each pressure stroke the wall 17 remains stationary and during the entire pressure stroke fuel is displaced out of the injection pump, so that in this way a maximum amount of fuel may be delivered. On the other hand, it is possible to adjust the sleeve 20 so that no fuel will be delivered during each pressure stroke, and this can be brought about by displacing the sleeve 20 downwardly, as viewed in the drawing, to a position where during the entire pressure stroke the wall 17 will move with the member 10 without remaining stationary while the member 10 continues to move, and thus there will be no delivery under these conditions.

In order to fully appreciate the invention, the operation of the structure described above and shown in the drawing without the valve means 12 should be considered. If the valve means 12 were omitted then there would be no difficulties during operation of the pump at high speeds. Under these conditions, even if the parts are relatively worn and even if the pump operates with a relatively light fuel, the length of time that the set of openings 35 remains out of communication with the openings 34 during each pressure stroke is so short that there is no danger of leakage of fuel from the pumping chamber back to the inlet passage means 34. In other words, during high speed operation there simply is insufficient time for the fuel to have an opportunity to leak back to the inlet passage means 34 during each pressure stroke, even if the valve means 12 were not present. However, during operation of the pump at a relatively slow speed the fuel could leak back to the inlet passage means 34 during each pressure stroke. The distance between the set of openings 35 and any one of the sets of inlet openings 34 at any given moment is at a maximum extremely small. Therefore, during relatively slow speed operation under certain conditions as when the pump operates with a relatively light fuel or when the parts become relatively worn, the fuel which is under relatively high pressure in the pumping chamber could indeed leak back between the surfaces of the cylinder 8 and the member 10 to the inlet passage means 34. If the distance between the set of openings 35 and the sets of openings 34 were made great enough to prevent this result from happening, the diameter of the cylinder 8 and the member 10 would be so large that the injection pump would have no practical utility. Therefore, under these conditions the valve means 12 functions to prevent leakage back to the inlet passage means 34. Because of the presence of the valve means 12 it is not possible for fuel between the valve 12 and the wall 17 to leak back to the inlet passages 34 during each pressure stroke. On the other hand, during high speed operation the inertia of the valve 12 is such that it cannot become seated and unseated with the precision and with the synchronism which is required. In other words, because of the inertia effects resulting from the high speed reciprocation and rotation of the member 10 the member 12 during high speed operation cannot reliably remain on its seat in a closed position during the entire part of each pressure stroke. However, this is immaterial since the openings 35 at this time cooperate with the discharge passages 34 to prevent the fuel from reaching the inlet passages 34. Therefore, while retaining all of the advantages of an injection pump designed for high speed operation, the addition of the valve 12 enables the structure also to operate in a perfectly satisfactory manner even under low speed operating conditions and even with relatively light fuels and even after the parts have been relatively worn so that the seal between the exterior surface of the member 10 and the inner surface of the cylinder 8 is not absolutely fluid-tight at the high pressure prevailing during a pressure stroke within the cylinder 8. It will be noted also that with the structure of the invention the disadvantage of not being able to use a pump designed for low speed oper-

ation also at high speed operation is avoided, so that in this way with the structure of the invention the same pump can be used for operation both at low speeds and high speeds and with all type of fuel as well as under all operating conditions.

The injection pump of the invention is particularly suitable for use with light fuels and high speed Otto engines. Such fuels because of their low viscosity require an effective structure for preventing leakage back to the inlet of the pump from the pumping chamber. However, the injection pump of the invention is also equally well suited for operation with other fuels.

It will be understood that each of the elements described above, or two or more together, may also find a useful application in other types of pumps differing from the types described above.

While the invention has been illustrated and described as embodied in injection pumps, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In an injection pump, in combination, a cylinder having a pumping chamber therein; piston means in said cylinder adapted to reciprocate therein along pressure and suction strokes; inlet passage means leading to said pumping chamber; discharge passage means leading from said pumping chamber; control means connected to said piston means for movement therewith and cooperating with said inlet and discharge passage means for opening said inlet passage means during each suction stroke of said piston means and for closing said inlet passage means during each pressure stroke of said piston means, said control means opening said discharge passage means during each pressure stroke of said piston means and closing said discharge passage means during each suction stroke of said piston means, said control means being capable of preventing leakage of fuel back to said inlet passage means during the pressure strokes of said piston means when the pump operates at relatively high speeds but under certain operating conditions, as when the pump is used with a relatively light fuel or when the parts become worn, being incapable of preventing leakage of fuel back to said inlet passage means during pressure strokes of said piston means when the pump operates at relatively slow speeds; and valve means carried by said control means for movement therewith and located in the path of flow of fuel from said inlet passage means to said pumping chamber for preventing fuel from leaking back to said inlet passage means during pressure strokes of said piston means at relatively slow speeds of operation of the pump, said valve means, because of its inertia, being incapable of maintaining the pumping chamber closed off from said inlet passage means during the entire pressure strokes of said piston means when the pump operates at relatively high speeds, whereby said control means and said valve means cooperate to prevent leakage back to said inlet passage means during all speeds of operation of the pump.

2. In an injection pump which is adapted to operate at relatively low as well as at relatively high speeds, in combination, a cylinder having a pumping chamber; piston means located in said cylinder and adapted to reciprocate therein along pressure and suction strokes; inlet passage means providing a path of fuel flow into said

pumping chamber; discharge passage means providing a path of fuel flow out of said pumping chamber; control means connected to said piston means for movement therewith and cooperating with said cylinder for opening said inlet passage means during each suction stroke of said piston means and for closing said inlet passage means during each pressure stroke of said piston means, said control means opening said discharge passage means during each pressure stroke of said piston means and closing said discharge passage means during each suction stroke of said piston means and said control means, under certain operating conditions as when the pump operates with a relatively light fuel or when the parts become relatively worn, being incapable of preventing leakage of fuel during pressure strokes of said piston means back to said inlet passage means at relatively low speeds of operation of the pump; and valve means carried by said control means for movement therewith and located between said inlet passage means and said pumping chamber for preventing flow of fuel back to said inlet passage means during pressure strokes of said piston means at relatively low speeds of operation of the pump, said valve means, because of its inertia, being incapable of maintaining said inlet passage means closed off from said pumping chamber during the entire pressure strokes of said piston means when said pump operates at relatively high speeds, whereby said control means and said valve means cooperate to prevent leakage of fuel back to said inlet passage means during pressure strokes of said piston means at relatively low as well as at relatively high speeds of operation of the pump.

3. In an injection pump adapted to operate at relatively low as well as at relatively high speeds, in combination, a cylinder having a pumping chamber and formed with a pair of passages extending through the wall of said cylinder and axially displaced with respect to each other, one of said passages forming an inlet passage providing for a path of fuel flow into the pumping chamber and the other of said passages forming a discharge passage providing for a path of fuel flow out of said pumping chamber; an elongated member slidably located in said cylinder and having one portion which forms a piston means and another portion formed with a pair of passages cooperating respectively with said pair of passages of said cylinder and forming a control means for controlling the opening and closing of said cylinder passages; means cooperating with said elongated member for axially reciprocating the same and for rotating the same in said cylinder so that the portion of said member which forms said piston means will reciprocate in said cylinder along pressure and suction strokes and the portion of said member which forms a control means will cooperate with said cylinder passages to close said inlet passage during each pressure stroke of said piston means and to open said inlet passage during each suction stroke of said piston means, said control means cooperating with said discharge passage for closing the latter during each suction stroke of said piston means and for opening said discharge passage during each pressure stroke of said piston means, and said member, under certain operating conditions as when the pump works with a relatively light fuel or when the parts become relatively worn, being incapable of preventing the leakage of fuel from said pumping chamber back to said inlet passage during each pressure stroke of said piston means when the pump operates at relatively low speeds; and valve means carried by said member in said portion thereof which forms said control means for closing off the pumping chamber from said inlet passage during each pressure stroke of said piston means when the pump operates at relatively low speeds, said valve means reciprocating and rotating with said member and because of its inertia being incapable of reliably closing off the pumping chamber from said inlet passage during the entire part of each pressure stroke of said piston means.

when the pump operates at relatively high speeds, whereby the valve means and the control means cooperate to prevent the flow of fuel back to said inlet passage means during each pressure stroke of said piston means when the pump operates at relatively low speeds as well as when the pump operates at relatively high speeds.

4. In an injection pump capable of operating at relatively low as well as at relatively high speeds, in combination, a cylinder having a pumping chamber in its interior and formed in its wall with an inlet passage means providing for fuel flow into said pumping chamber and, axially spaced from said inlet passage means, with a discharge passage means providing for fuel flow out of said pumping chamber; an elongated member slidably located in said cylinder, having a tubular portion in said pumping chamber and overlapping both of said passage means and having a solid portion next to said tubular portion, said solid portion forming a piston means and said tubular portion of said elongated member being formed with passages cooperating with said inlet and discharge passage means and forming a control means; drive means cooperating with said member for reciprocating and rotating the same in said cylinder, said piston means reciprocating along pressure and suction strokes when said member is reciprocated by said drive means and said control means cooperating during driving of said member with said inlet and discharge passage means for closing said inlet passage means during each suction stroke of said piston means and for opening said inlet passage means during each suction stroke of said piston means, said control means cooperating with said discharge passage means for closing said discharge passage means during each suction stroke of said piston means and for opening said discharge passage means during each pressure stroke of said piston means, and said member, under certain operating conditions as when the pump operates with a relatively light fuel or when the parts become relatively worn, being incapable of preventing leakage of fuel back to said inlet passage means during pressure strokes of said piston means when the pump operates at a relatively low speed; and valve means located in said tubular portion of said member between the passage thereof which cooperates with said discharge passage means and the passage thereof which cooperates with said inlet passage means for closing off the pumping chamber from said inlet passage means during pressure strokes of said piston means when the pump operates at relatively low speeds, said valve means, because of its inertia during reciprocation and rotation of said member when the pump operates at relatively high speeds, being incapable of maintaining said pumping chamber closed off from said inlet passage means during the entire part of each pressure stroke of piston means when the pump operates at relatively high speeds, whereby said control means and valve means cooperate to prevent leakage of fuel back to inlet passage means during both relatively high and relatively low speeds of operation of the pump.

5. In an injection pump as recited in claim 4, said tubular portion of said member being formed in its interior with a shoulder providing a valve seat for the valve means.

6. In an injection pump, in combination, a cylinder having in its interior a pumping chamber and formed with an inlet passage means providing for fuel flow into said pumping chamber and, axially spaced from said inlet passage means, with a discharge passage means providing for flow of fuel out of said pumping chamber; an elongated member slidably located in said cylinder and means cooperating with said member for reciprocating and rotating the same in said cylinder, said elongated member having one portion which extends transversely across said cylinder and forms a piston means which reciprocates therein along pressure and suction strokes and having another portion which is tubular and which is formed with passages which during rotation of said elongated member open said inlet passage means during each suction stroke of said piston means and closes said inlet passage means during each pressure stroke of said piston means and which during each pressure stroke of said piston means opens said discharge passage means of said cylinder and closes said discharge passage means during each suction stroke of said piston means, said elongated member, under certain operating conditions as when the pump operates with a relatively light fuel or when the parts become relatively worn, being incapable of preventing leakage of fuel back to said inlet passage means during pressure strokes of said piston means when the pump operates at relatively low speeds, said tubular portion of said member being formed in its interior with an axial, stepped bore having intermediate its ends a shoulder located between the part of said tubular portion which cooperates with said discharge passage means and the part thereof which cooperates with said inlet passage means and said shoulder forming a valve seat; a valve member guided in said tubular portion for axial movement between open and closed positions and engaging said valve seat in its closed position, said valve member engaging said valve seat during each pressure stroke of said piston means when the pump operates at relatively low speeds so as to cut off the pumping chamber from said inlet passage means at low speeds of operation of the pump, and said valve member due to its inertia, when rotating and reciprocating with said elongated member during operation of the pump at relatively high speeds, being incapable of remaining on said valve seat during the entire part of each pressure stroke of said piston means when the pump operates at high speeds, whereby said tubular portion of said elongated member and said valve member cooperate to prevent flow of fuel back to said inlet passage means during both low and high speeds of operation of the pump.

7. In a pump as recited in claim 6, means cooperating with said cylinder for controlling the volume of said pumping chamber so as to regulate the amount of fuel discharged therefrom during each pressure stroke of said piston means.
